REMOTE CONTROL FOR RADIORECEIVERS

Frederick K. Vreeland, Montclair, N. J.

Application July 24, 1929, Serial No. 380,515

2 Claims. (Cl. 250—40)

The invention herein described is a remote control system for radio receivers.

The object of the invention is to control the station or frequency selection and other operating features of a radio receiver from a point or points located at a distance from such receiver. A further object of the invention is to simplify the process of control by making the usual selector dial unnecessary, and still further to simplify the process by substituting automatic features for manual adjustments. In the fullest embodiment of the invention the operation of the receiver may be reduced to the single act of pressing a button, the selecting of the station by the adjusting of the receiver to the proper signal frequency and the governing of the output level being accomplished automatically.

Other features of the invention include means whereby the receiver may be controlled from any one of several different points, and the output of the receiver heard at any one or any group of such points, and means for preventing confusion or conflicting operation which might result from the several operators working at cross purposes.

In carrying out the present invention I preferably employ, in certain embodiments of the invention, features that are disclosed in my patents No. 1,666,518, April 17, 1928, No. 1,682,874, 30 September 4, 1928, No. 1,725,433, August 20, 1929, and No. 1,730,987, October 8, 1929 and applications Serial Nos. 300,172 and 377,409 relating to radio receivers having a band reception characteristic, also certain features of my application 35 Serial No. 297,337 relating to automatic governors for electrical amplifiers. These features are highly desirable when combined with the other elements of my remote control system. The automatic governor permits the operation 40 of a key or push button control for selecting stations whose signal strengths differ over a wide range, maintaining the output at a predetermined level without manual adjustment, irrespective of the input signal strength. The 45 band reception feature is also valuable, not only because of the fidelity of tone that it achieves together with high selectivity, but also because the band characteristic, if the reception band is made a little wider than the transmission band, 50 permits some tolerance in the operation of the remote control mechanism without distortion or weakening of the signal, thus avoiding the necessity of great mechanical precision in the mechanism. These latter results are impossible when 55 a sharply tuned receiver is employed.

In the drawings Figure 1 shows schematically a typical embodiment of the invention.

Figures 2 and 3 show details of a typical construction of the automatic selector mechanism.

Figure 4 shows a typical construction of one of the remote control units.

Figure 5 is a schematic view showing one form of a band receiver.

In the operation of a radio broadcast receiver it is usual to operate the frequency selector by 65 the rotation of a shaft or member which actuates variable circuit elements which in turn perform the frequency selection. This shaft or frequency selector member is ordinarily operated by a knob or other manual control. It is 70 also usual to control the output level for each individual station by a volume control, also manually operated. It is usual furthermore to turn the electrical power on or off by a manually operated switch located at the receiver. When the 75 present invention is employed all of these manual operations at the receiver are made unnecessary so that the receiver may be located in any convenient or even relatively inaccessible place. In the preferred embodiment of the invention 80 any or all of these operations are performed automatically, but under the control of an operator or operators at one or more remote points.

The frequency selector is operated preferably 85 by an electric motor or other prime mover, and the selection of the desired station or signal frequency is controlled, in one embodiment of the invention, by the operation of a master dial, which causes synchronous or otherwise corresponding motion of the frequency selector member 90 of the receiver, thus making it possible to adjust the receiver at will for the reception of any wave frequency within its range. In another embodiment, the operation is still further simplified by pressing a button or key corresponding to any desired signal frequency, thus setting in operation an automatic selector which 95 adjusts the receiver for the selection of the desired frequency. Another feature of the invention is a very simple device for setting the 100 various station selectors so that each will select any desired frequency.

In the preferred embodiment, when the desired signal frequency is selected the output 105 level of the signal is automatically governed and maintained at a predetermined value, irrespective of the input signal strength, and the strength of the output signal may be altered at will by an output control or attenuator located at the control point. The output signal 110

strength at any or all of the several control points may be independently adjusted, and when so adjusted the desired output level will be automatically maintained at each of such points 5 irrespective of the input signal strength.

In Fig. 1, which represents a convenient arrangement embodying these various features, 1 and 2 represent two typical control units, each associated with its own loud speaker Y, through 10 which the output is delivered. 3 indicates a radio receiver, which is shown in diagrammatic form, since the invention is not limited to any particular receiver construction, although it should have preferably a band response characteristic, as in the arrangement shown in Fig. 5. 15 4 is the automatic selector mechanism, and 5 is an automatic governor, such as that shown in my application Serial No. 297,337. It will be understood that certain of these features may 20 be omitted or modified, but they are all desirable for securing the fullest advantages of the invention.

In the receiver 3, S indicates the shaft or selector member which controls condensers or 25 other variable circuit elements for frequency selection. The electrical selective system, controlled by this element, is preferably one having a band response characteristic, and may include a band selector or a spaced band amplifier or 30 both, as set forth in my patents and applications above mentioned. Q is a dial or equivalent frequency indicating device of any suitable form which may be used for observing the setting of the frequency selector. This setting may 35 be performed manually by means of the control knob N, as an alternative to the remote control operation. The shaft or spindle S' of the control knob N is connected by a worm or other suitable gearing W to a motor M whereby the 40 automatic or remote operation of the selector is effected. The shaft S' is preferably connected to the gearing W by a coupling that permits independent motion of the shaft and gearing, such as a slip connection w, so that the manual 45 control N may be operated without rotating the motor and gearing. The device Q is shown as connected to the shaft S' by a belt and pulleys.

The operation of the motor M is controlled by the automatic selector mechanism 4, through 50 one or the other of two interconnected remote control devices, one being a master dial control which functions through the continuously acting element V₁, and the other a button or key control which functions through the operation of 55 the individual selector positioning elements D with their associated parts. Either or both of these control mechanisms may be embodied in the apparatus as desired.

The key control mechanism comprises a plurality of selector positioning elements here shown as discs D, which may be of any desired number corresponding to the selector buttons a, b, c, d, e in the control units 1 and 2. Each of the selector positioning elements operates a pair 60 of electrical contacts which are preferably arranged with a common terminal and two free terminals. A typical construction of these discs and their associated parts is shown in the detail drawings, Figs. 2 and 3. The discs D are made 65 each with a contact sector, here shown as a semi-circular peripheral portion of larger diameter, the remaining semi-circular part being made of smaller diameter. Each disc is provided with two contact brushes C and CC, 70 here shown as located at opposite ends of

a diameter of the disc D. These contact brushes are so arranged that when the disc D is in the position shown neither of them makes contact with the disc, but if the disc is rotated by the smallest amount, one or the other brush will make contact with the contact sector, depending on the direction of the rotation. All of the brushes C are connected to one terminal of the motor M and all of the brushes CC are connected to a second terminal of the motor M. These terminals are so arranged that when a current is sent through one of them, say that connected to the brush C, the motor operates in a clockwise direction and when current is sent through the other terminal, say that connected to the brush CC, the motor rotates in a counterclockwise direction. This reversing operation of the motor may be accomplished in any desired manner. For example: when a series commutator motor is used it may be provided with two field windings, wound or connected in opposite senses, one field winding connected to the brush C and the other to the brush CC. Changing contact from one brush to the other will cause a reversal of the motor field and so reverse the direction of rotation. If an induction motor is employed, the two terminals may be connected to separate stator windings causing opposite rotations, employing any desired construction as will be readily understood.

The selector positioning elements D are insulated from each other, and each has associated with it a separate contact brush A, whereby current is admitted to the particular element desired. The element thus energized will supply current through the corresponding brush C or CC, if either is making contact, causing the motor to operate and rotate the shaft S. The connections are so chosen that in either case the motor will drive the shaft in such a direction as to bring the element D into the position shown in Fig. 2, when both the brushes C and CC will break contact and the mechanism stops. The position in which the mechanism stops depends upon the angular position of the element D with respect to the shaft S. The angular positions of the several elements may be predetermined and fixed to correspond to certain desired signal frequencies, but preferably the elements are arranged to rotate on the shaft so that they may be adjusted at will. In the particular preferred construction shown in Fig. 3, the several discs or elements D are rotatably mounted on a hub H of insulating material 130 which is fixed to the shaft S. The elements D are separated by insulating spacers R which drive the elements by friction. The spacers R are held in a fixed angular position on the hub by keys or pins K, which however permit a certain small longitudinal movement to distribute the pressure uniformly among the elements. Uniformity of pressure is secured by spring washers JJ.

By means of this non-rigid connection any element D may be set in any desired angular position on the shaft, in which position it will remain, thus determining a particular positioning of the station selector.

The adjustment or setting of the several elements D is preferably accomplished by the arrangement shown in Fig. 2. The small diameter sector of the disc is provided with a notch X, the bottom of which enters an insert I of insulating material. A setting finger F is spring 145

mounted and adapted to press on the edge of the element D when operated by pressure on a spring-mounted button P. All the fingers F are connected to a line bus L, so that when a finger 5 makes contact with its corresponding element, current is admitted to the element D without passing through the spring A, and the motor rotates the element until it comes into the position shown in Fig. 2, in which the brushes C 10 and CC are out of contact and the notch X is opposite the point of the finger F. The spring pressure exerted by the button P when pressed by the operator then causes the finger to enter the notch X where it rests on the insulating 15 insert I, holding the element D in the position shown without making electrical contact therewith. The insert I is not essential, since the brushes C and CC alone will open the circuit, but it is desirable in case of inaccurate alignment of the parts. When the disc is thus held 20 in fixed position the shaft S may be rotated manually by the knob N and the receiver tuned to any desired signal frequency in the ordinary way. When thus tuned the button P is released and the corresponding selector element D remains in the position in which it is set. Thereafter the element D, when energized 25 through the contact spring A, will operate the mechanism to bring the selector to the frequency corresponding to the position in which the disc is set.

This setting may be accomplished for each of the several elements D by operating the corresponding button P. Each disc may thus be set 30 for a different signal frequency and when so set will, when energized, always cause the selector to be brought to the corresponding signal frequency. The energizing of the several elements D through their corresponding contact 35 springs A is accomplished by operating selector keys or buttons a, b, c, d, e, located in any one of the control units, say control unit 1. When any one of these selector keys is closed it connects the corresponding spring A and element 40 D with the key bus L'. If the key bus L' and the line bus L are energized the mechanism will be set in operation to bring the frequency selector to the position determined by the particular key a, b, c, d, e that is closed.

50 The line bus L may be energized by closing any one of the switches M₁, M₂ or M₃, the first two switches being located in the control units 1 and 2, and the third switch M₃ being located at the receiver 3. The switches M₁ and M₂ are preferably made with two contact points, as shown, the second contact point serving to energize the key bus L'. The key bus L' is thus energized only by closing the switch in its own control unit, as M₁. If any one or more of the 55 switches M₁, M₂ or M₃ is closed, the line bus L will be energized, thereby applying power to the receiver 3, and the motor M. If either of the switches M₁ or M₂ is closed, the corresponding key bus L' will also be energized so that any desired one of the selector keys a, b, c, d, e, in 60 the same control unit may be operated, setting the frequency control mechanism in operation. The keys in the other control unit or units will not then be operative. When rotation of the selector shaft ceases the receiver will then be responsive to the signal frequency corresponding to the key that is closed.

65 The output of the receiver 3 is delivered through terminals O to one or more of the sound projectors or loud speakers YY operated by the

receiver. Each of these loud speakers is preferably controlled by an attenuator At, whereby the loudness of the sound may be adjusted, and a switch whereby the speaker may be turned on or off.

80 In circuit between the output terminals O and the speakers YY is an output control relay OR which, when it operates, opens the circuit and disconnects the speakers from the receiver. The operation of this relay is controlled by the selector mechanism. In the arrangement shown the relay has two windings which are connected respectively to the two sides of the motor control circuit as shown, so that whenever the mechanism energizes the motor to operate the frequency selector the loud speakers will be disconnected and will remain disconnected until the frequency selection is complete and the mechanism stops. The loud speaker or speakers will then operate on the selected signal. Undesired signal or local noises during the operation of the mechanism are thus avoided. When a selector key is closed the output sound ceases and the speakers remain silent until the sound of the selected signal is heard.

90 5 is an automatic governor, that is, a device whereby the strength of the received signal automatically regulates the over-all gain of the receiver. It operates to maintain the output level of the signals delivered by the receiver at substantially the desired value, irrespective of the input signal strength. The form of governor shown is of the type set forth in my co-pending application 297,337 filed Aug. 3, 1928, comprising a rectifier R, which derives an electromotive force from the output terminals O through the adjusting potentiometer p and transformer T₁, which it rectifies thereby setting up a floating charge in the condenser C', which floating charge impresses an electromotive force on the grid of a regulator tube B inserted in the plate circuit of the amplifier of the receiver 3. The floating charge in the condenser C', which depends upon the output level of the signal and on the setting of the potentiometer p, thus impresses a greater or less negative potential on the grid of the regulator tube B and thus regulates the power supply and hence the gain of the amplifier. R₂ is a series resistor for regulating the speed of response of the governor, and R₁ is a shunted resistor or leak for regulating the speed of recovery. By means of the governor 105 5 the output level of the signal delivered by the receiver 3 is maintained substantially constant 110 irrespective of the input signal strength, this level being determined by the setting of the potentiometer p.

115 It will be readily understood that any number of control units similar to that shown at 1 may be employed. A second control unit is 120 shown at 2, its various circuits being shown connected in parallel with the circuits of control unit 1.

125 To avoid confusion or conflict in the operation of two or more control units, pilot lights I and I' are employed to indicate the condition of the apparatus. When the power is turned on by the closing of any one of the line switches M₁, M₂ or M₃ the line pilot light I is illuminated in each of the control units. If the selector has been 130 operated by the closing of any one of the selector keys a, b, c, d, e, the light corresponding to the key closed is illuminated in each of the control units, so that an operator at any control unit can see the condition of the apparatus thus 135 140 145 150

avoiding conflicting operation of the selector keys. Preferably the selector keys are interlocked with each other and with the line switch, as will now be explained.

- 5 A convenient construction of the interlocking mechanism is shown in detail in Fig. 4. *a, b, c, d, e*, are the selector keys, corresponding to the parts so marked in Fig. 1. Each selector key is provided with a cam latch 6, cooperating with 10 an interlocking member 7 having a restoring spring 8, which holds it in position to engage the cam latches 6. When any key is depressed its latch 6 engages the interlocking member 7, which holds the key in the closed position. 15 The closing of the key operates the contact springs 9 to close the selector circuit connected to one of the brushes *A* of Fig. 1. When another key is depressed its cam latch, engaging the interlocking member, moves it against the 20 spring pressure, so that the first cam is released and opens the circuit of its contact spring 9. The second key is then held in closed position as before, and it remains closed until released by the interlocking member. 25 The interlocking member 7 has a connection with the line switch *M*₁ which operates to push the interlocking member against the spring 8 when the line switch *M*₁ is open. The opening of the line switch thus releases any selector key 30 that may be closed, clearing all the selector circuits. The circuits are thus in condition for being operated by any other control unit, such as 2, when the line switch *M*₂ is closed. When the line switch is open the selector keys are not 35 energized nor will they remain closed. The opening of the line switch, releasing the interlocking member, extinguishes all the pilot lights, showing that the lines are clear for the operation of any desired control unit. 40 The arrangement shown in Fig. 1 includes, in addition to the key controlled frequency selector units for setting the apparatus for any predetermined frequency, a remote dial control, whereby the selector may be adjusted at will for 45 any desired frequency within its range by operating the remote control dial *V*₂ shown in the control unit 2. Control dial *V*₂ operates a voltage divider, excited by a source of electromotive force *E*. A similar and preferably equal voltage 50 divider *V*₁ is operated by the selector shaft *S* of the receiver 3 and is excited also by the source of electromotive force *E*. When the two voltage dividers *V*₁ and *V*₂ are set in corresponding positions there will be no potential difference between 55 their respective contact arms. But if these arms are not in corresponding positions there will be a potential difference whose magnitude depends upon the amount of the displacement and whose sign depends on the direction 60 of the displacement of the voltage divider *V*₂ with respect to *V*₁. *PR*₁ and *PR*₂ are polarized relays arranged to be operated by the potential difference between *V*₁ and *V*₂. If the displacement of *V*₂ with respect to *V*₁ is in one direction 65 the potential difference will be positive and one of the relays, say *PR*₁, will operate. If the displacement of *V*₂ is in the opposite direction the potential difference will be negative and the other polarized relay *PR*₂ will function. The 70 functioning of either relay preferably operates a second relay *CR*₁ or *CR*₂ of more rugged construction, which in turn closes a contact connected to one of the brushes *C* or *CC* of the selector mechanism. The use of the second relay 75 *CR*₁ and *CR*₂ is desirable to handle the rel-

atively large current required to operate the motor *M* while permitting a very sensitive construction of the polarized relays *PR*₁ and *PR*₂, so that the system will respond to a very small relative displacement of the voltage dividers *V*₂ and *V*₁. Any such displacement in either direction will set in operation one set of relays *PR*₁, *CR*₁ or *PR*₂, *CR*₂, depending on the direction of the displacement and this will close one of the motor control circuits *C* or *CC*, the connections being so chosen that the resulting rotation of the motor *M* and shaft *S* will bring the voltage divider *V*₁ into the position corresponding to that of *V*₂. When this position is reached the potential difference becomes zero, the relays release and the motor stops. An additional contact key *f* is preferably employed in control unit 2, so that the remote dial control may be thrown on or off by the operation of this key, any other key being simultaneously opened by the interlocking mechanism.

It will thus be seen that when the key *f* is closed, any motion of the dial voltage divider *V*₂ will cause a motion of the frequency selector mechanism in a direction corresponding to that of the voltage divider *V*₂ and this motion continues until the voltage divider *V*₁ comes into the position corresponding to that of *V*₂. Thus the selector may be turned at will in either direction and by any desired amount by the operation of the remote control dial *V*₂ and the selector may thus be set for any desired frequency. Only one remote selector dial *V*₂ is shown in the drawings, but it will be readily understood that any number of such control dials may be employed, either in conjunction with key selectors as shown, or as independent dial selector units, as may be desired.

It will be seen from the above description that the arrangement of Fig. 1 provides for complete control of all the functions of a radio receiver from one or more distant points, whether by the operation of keys for selecting predetermined frequencies or by the arbitrary selection of any desired frequency, provides means for governing automatically the output level of the received signals irrespective of the input signal strength, and provides also means for determining the magnitudes of the output levels at the several receiving points independently, so that a signal may be received at any one or any group of such points, each with its own desired output strength, such output strength being determined at will at the corresponding remote control point. It includes also means for interlocking the several control circuits to prevent conflicting operation, and provides at each control point pilot lamps or signals to indicate the operating condition of the system. The apparatus is thus completely under control and the process of control- 135 ling it is reduced to the greatest simplicity.

What I claim is:

1. A remote control apparatus for radio receivers wherein are combined a frequency selector, a motor operating such frequency selector, means located at a distance for initiating the operation of the motor, and means in operative relation with the selector for determining the direction and extent of the operation of the selector, said means including a selector positioning element operatively connected to the selector, electrical connections co-operating with the selector positioning element to control the operation of the motor, and means for holding the selector positioning element in neutral position.

while the frequency selector is moved with respect to the selector positioning element, and the selector positioning element is set to correspond to any desired signal frequency.

- 5 2. A remote control apparatus for electrical receivers wherein are combined a frequency selector, a motor operating the selector, a plurality of selector positioning elements operatively connected to the selector, a pair of electrical 10 contacts having a common terminal and two free terminals operated by each selector positioning element, a common connection from one free terminal of all the pairs, a second common

connection from the other free terminal of all the pairs, connections from the two common connections to the motor causing, when energized, rotation in opposite directions, electrical connections from the contacts, and means located at a distance for electrically energizing at will any one of the common terminals and causing the selector to be moved in the direction and to the position determined by the particular selector positioning element whose contact terminal is energized. 80 85
